UNITED STATES PATENT OFFICE

BANCROFT G. BRAINE, OF NEW YORK, N. Y., ASSIGNOR TO THE RAIL JOINT COMPANY,
OF NEW YORK, N. Y., A CORPORATION OF NEW YORK

RAIL JOINT CONSTRUCTION

Application filed July 14, 1930. Serial No. 467,875.

This invention relates to a novel construction for rail joint bars having for a primary object ease of application, correct mechanical functioning and increased life in service with consequent economy in the use of metal in the manufacture of the bar.

To that end the invention contemplates a special formation of the fishing surface at the head of the bar and of the fishing surface at the foot of the bar to provide an adequate remedying of certain defects due to present practice, and to materially strengthen the joint structure as to its stress resisting capacity. Also, the novel formation of the fishing bearing surfaces causes the rail and the joint bars to function as independent units, thus permitting a more accurate and efficient means of determining the requisite joint bar. Also, in a more general way the invention provides a construction for rail joint bars intended to cause the rail joint to act as a continuous beam with the load distributed over as much of its length as possible, to make the load on the rail ends, within the joint, more nearly a uniform load distributed over a considerable length of the rail ends.

With these special objects in view the invention consists in the novel structural formation of the joint bars of a rail joint herein described, illustrated and claimed, and while susceptible of modification and of adaptation to different types of joint bars, preferred and practical examples of the invention are shown in the accompanying drawings, in which:

Figure 1 is a cross-section of a rail joint having the novel features contemplated by the present invention according to one practical embodiment of the latter.

Figure 2 is a view similar to Fig. 1 of another practical embodiment of the invention.

Figure 3 is a view similar to Fig. 2 but illustrating a substantially reverse application of the invention to the bar to that shown in Fig. 2.

Figure 4 is a view similar to Figs. 1, 2 and 3, illustrating a rail joint bar combined with a fishing shoe or shim, the combined struc-

ture embodying the practice of the present invention.

Figures 5 and 6 are views similar to Figs. 1 to 4 illustrating the incorporation of the invention in a continuous type of rail joint.

Figure 7 is a perspective view illustrating an embodiment of the invention in which interrupted line or substantial line contact is provided between a joint bar and the rail.

Figure 8 is a view similar to Figs. 1 to 3 illustrating an alternative embodiment of the invention.

Figure 9 is a view similar to Fig. 4 illustrating a further alternative embodiment of the invention.

As the present invention has particularly in view a structural formation of the fishing bearing surfaces of the bar which admit of a new and more efficient functioning of the rails and of the joint bars, the action of the joint bar under load should be noted as a premise to a consideration of a feature of improvement contributed by the present invention. On that subject it is now generally accepted that in the flexure of a rail joint under vertical load, the pressure of the rail is applied at the top of the joint bars near the rail ends at a point called the centroid of bearing pressures and that the reaction pressure between the bar and the rail is at the reactions centroid, which is located near the ends of the joint and between the lower surface of the joint bar and the top surface of the rail base. These bearing pressures produce horizontal frictional resistance in the direction of the length of the joint bar and the moment of these couples contribute to the transmission of moments from the rail to the joint bars. The greater flexibility of the joint bars and the difference in the flexure of the rail and the joint bars at points along their length will leave a minute space between the joint bars and the rail surfaces at points away from the areas of bearing pressures and reaction pressures. With the ordinary arrangement of surface contacts—flat at both head and base bearings—it not only centralizes the wear at these areas of pressure, but also prevents an

adjusting of the flexure of the joint and rail ends.

By curving laterally one or both of these contacts, we start, with a well fitting joint bar, with the load distributed along the full length with little or no longitudinal frictional resistance to prevent co-ordination of the flexure of the joint bar and the rails, and thereby more nearly approximate a joint bar of the continuous beam type having the load distributed over a considerable portion of its length, with the rail end functioning with a more nearly uniform load distribution.

It will be seen, therefore, that the essential feature of the present invention is to provide the joint bar 1 with a laterally curved fishing surface 2 at the upper-side of its head for engagement with the underside of the head of the rail R, and with a laterally curved fishing surface 3 at the underside of its foot 4 for engagement with the upperside of the rail base flange. Each of the surfaces 2 and 3 may be the arc of a circle or any single or compound curve or the substantial equivalent thereof, and the surface 2 at the upperside of the head of the bar preferably is curved to merge gradually into the fillet arc 5 of the bar head. Thus, the line or substantial line contacts provided by the curved fishing bearing surfaces 2 and 3 may be centralized laterally from the rail center and may be brought more nearly in line with the web of the joint bar, which permits designing the joint bar more nearly of the I-beam or Z-bar type and at the same time permits the joint bar to flex about its horizontal gravity axis, which latter condition provides for less strain on the bolts.

It will of course be understood that the laterally curved fishing bearing surfaces 2 and 3 may extend the full length of the joint bar and have bearing contact with the opposed fishing surfaces of the rail throughout the length of the joint in order that the purposes of the invention may be effectually fulfilled. Furthermore, it will be understood, of course, that the invention is not limited to the degree or type of the curve on which the arcuate bearing surfaces are designed, as this necessarily would vary according to the limitations of the method of manufacture and according to the type and weight of the rail. However, in all embodiments of the invention a distinctive feature is the one already alluded to, namely, that of having the head and base fishing surfaces of the joint bar transversely curved, and in the preferred embodiment, as illustrated in Fig. 1 of the drawings, to have the points of bearing contact provided by said curved surfaces 2 and 3 approximately in line with the web of the joint bar.

A practical embodiment of the invention is shown in Fig. 1 of the drawings wherein

all of the several features described are consolidated in an angle type of splice bar, while in Fig. 2 of the drawings is shown a form of angle bar wherein the head of the bar, in addition to having the upper laterally curved fishing bearing surface 2, also is formed at its inner side with a rounded inner bearing projection 5^a, which ultimately may seat itself in the head fillet 6 of the rail. That is to say, in the rail joint construction shown in Fig. 2 of the drawings, wherein the joint bar has the top laterally curved bearing surface 2 and the bottom laterally curved bearing surface 3, the purpose is to have the joint bar function with a constantly increasing bearing as the lower portion of the joint bar is pulled in, under adjustment, and this is accomplished by reason of the fact that the curved head surface 2 rolls on the underside of the rail head and finally into the fillet 6 of the rail, producing the so-called headfree joint. Also this construction of Fig. 2 permits of slight variations in the fishing of the rails and any other slight irregularities of surface.

In Fig. 3 of the drawings is shown a modification of the invention which is substantially the reverse of that shown in Fig. 2 of the drawings. That is to say, the head of the joint bar is provided with the laterally curved fishing bearing surface 2, with the laterally curved bottom fishing bearing surface 3, and also at its foot with the inner bearing projection 7 adapted ultimately to seat itself in the bottom rail fillet 8 as the top of the bar is pulled in, under adjustment.

As illustrative of the scope and range of the invention, reference is made to Fig. 4 of the drawings wherein a fishing shoe or shim 9 is employed. This fishing shoe fits within the fishing of the rail and is provided at its upper end with a top flange 10 formed on its upperside with a laterally curved fishing bearing surface 11 which has a bearing contact with the underside of the rail head. At its bottom the said shoe is provided with an outwardly directed flange 12 formed at its lowerside with a laterally curved fishing bearing surface 13 engaging the upperside of the rail flange. The said shoe 9 is of a channel form and at its outside is provided with a fishing space having the upper flat bearing surface 14 and the lower flat bearing surface 15 against which surfaces 14 and 15 the head and foot of the rail joint bar designated 16 are seated. When the bolts of the joint are placed in the structure of Fig. 4 the shoe 9 and the joint bar 16 provide a unitary rail joint structure having the characteristics and functions of the joint bars previously described herein.

Manifestly, with respect to the shoe or shim illustrated in Fig. 4 the same may be

formed in one-piece, as shown, to extend either the full length or only partially the length of the joint, or separate shoes or shims may be provided for the head and the base of the bar, and in either case the shim or shims, as the case may be, may be welded or otherwise secured to the bar and may have either continuous or interrupted line or substantial line contact with the rail.

As further illustrative of the scope of the invention reference is made to Figs. 5, 6, 7, 8 and 9 of the drawings. In Figs. 5 and 6 the joint bar 1^a is illustrated as of the continuous type having a base flange 17 underlying the base of the rail, and in accordance with the invention the upper side of this base flange 17 is provided with a rounded bearing surface 18 for line or substantial line contact with the bottom surface of the rail. Obviously, the upper part of the bar may be of the design shown in either of Figs. 1, 2 or 3 as suggested by Fig. 5 wherein the design is similar to the design shown in Fig. 1, or the upper, inner corner of the bar 25 may be formed for so-called headfree contact with the head fillet of the rail as indicated in Fig. 6. On the other hand, the head and base fishing surfaces of the bar may be flat or substantially flat, and rounded surfaces 19 and 20 may be provided on the underside of the rail head and on the underside of the rail flange for line or substantial line contact with said joint bar surfaces 19 and 20 as illustrated in Fig. 8, and 35 in any instance the rounded contact surface of any of the bars, or of the rail, may be continuous longitudinally or may be interrupted at spaced points as indicated at 21 in Fig. 7 of the drawings.

Figure 9 of the drawings illustrates a substantial reversal of the embodiment of the invention shown in Fig. 4. That is to say, according to the embodiment of the invention illustrated in Fig. 9, a shoe 9^a, which 45 may be formed either in one piece or in a plurality of sections, fits the fishing of the rail R and is inclusive of top and bottom flanges 10^a, 12^a respectively, having laterally curved bearing surfaces 11^a, 13^a, respectively, 50 for either continuous or interrupted line contact with the head and the base of the joint bar 16^a.

With respect to the line or substantially line contact between the joint bar and the rail afforded by the present construction, this manifestly constitutes a means to the end that as wear takes place there is permitted an adjustment to accommodate the 55 points of greatest pressure without affecting materially the maintaining of some bearing along the full length of the joint bar. Furthermore, the said line or substantially line contact serves to reduce the requisite 60 bolt tension and at the same time permits

relatively free contraction and expansion of the rail joint structure.

I claim:

1. A rail joint construction including the rail, and a joint member provided with upper and lower laterally curved surfaces respectively contacting with the flat underside of the rail head and the flat upper side of the rail flange. 70

2. A rail joint construction including the rail, and a joint member provided with upper and lower laterally curved surfaces respectively contacting with the flat underside of the rail head and the flat upper side of the rail flange throughout the length of the joint. 75

3. A rail joint construction including in combination with the rail, the joint bar having laterally curved fishing bearing surfaces at the upper side of its head and at the underside of its foot, said fishing bearing surfaces having bearing points of contact approximately in line with the web of the joint bar. 80

4. A rail joint construction including the rail, and a joint member provided with upper and lower surfaces respectively having line or substantially line contact with the underside of the rail head and the upper side of the rail flange. 85

5. A rail joint construction, including the rail, the joint member cooperating at its head with the head of the rail and at its base with the base of the rail, and means affording line contact between the rail and the joint member at both of said places of cooperation of these elements. 90

In testimony whereof I hereunto affix my signature.

BANCROFT G. BRAINE.
